UNITED STATES PATENT OFFICE.

CHARLES A. BELL, OF MEDINA, NORTH DAKOTA.

COMBINED COLLAR BUTTON AND TIE FASTENER.

Application filed July 21, 1924. Serial No. 727,327.

To all whom it may concern:

Be it known that I, CHARLES A. BELL, a citizen of the United States, residing at Medina, in the county of Stutsman and State of North Dakota, have invented new and useful Improvements in Combined Collar Button and Tie Fasteners, of which the following is a specification.

This invention contemplates the provision of a combined collar button and tie fastener, the button including a hollow shank adapted to be passed through the button holes of the garment and collar, and adapted to receive a cooperating member adapted to be secured to the tie, together with means for holding the component parts fixed relatively whereby the tie can be easily and quickly placed in position upon the collar, and immovably held in said position so as to always present a neat appearance.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view showing how the invention is used.

Figure 2 is a front elevation of a tie showing the invention in plan and associated with said tie.

Figure 3 is a longitudinal sectional view through the device forming the subject matter of the invention with the tie removed.

Figure 4 is a perspective view of the device with the tie removed.

Figure 5 is a view of the tie carrying member.

Figure 6 is a detail view of the locking element.

The combined collar button and tie fastener forming the subject matter of the invention essentially consists of three parts, one of which includes the base 10 of the button from which extends a hollow shank 11, the shank being formed at its free end with a head 12 which includes a tapered or beveled portion 13 for a purpose to be hereinafter described. The base 10 is thickened as at 14 and formed with a slot to receive the slide or locking element 15 clearly shown

in Figure 6. This slide is formed with a longitudinal slot 16 which receives a pin 17 passed transversely through the thickened portion 14 of the base of the button as clearly shown in Figure 3. This piece manifestly cooperates with the opposed ends of the slot 16 to limit the movements of the slide. Depending from the lower end of the slide is a reduced extension 18. The slide constitutes one of the three parts of the device, the remaining part being in the nature of a tie carrying member including a small plate 19 from one side of which projects the shank or member 20, the latter being formed with an opening 21 to receive the reduced extension 18 of the slide when the parts are operatively associated in the manner shown in Figure 3. It will be noted that the plate 19 of the tie carrying member is obliquely disposed with relation to the shank or member 20, and has a plurality of openings 22 so that the tie 23, either a bow tie or a four-in-hand tie can be sewed or otherwise suitably secured to the plate 19. By reason of the angular arrangement or disposition of the plate 19, it is manifest that the tie can be properly arranged on the collar to present a neat appearance, the head 12 of the shank 11 being formed with a beveled or inclined portion 13, to permit the plate 19 to be properly set at an angle for this purpose, when brought into contact with the head 12. The invention is very simple in construction, and can be conveniently handled when putting on a collar and tie or removing the same from the neck band of a shirt.

In practice the shank 11 of the button is passed through the button holes of the neck band of the shirt indicated at 24 in Figure 1, and also passed through the button holes in the adjacent ends of the collar indicated at 25 in Figure 1, with the thickened portion and slide arranged uppermost so that it can be conveniently reached by one finger of the user. The slide is now elevated to remove the reduced extension 18 above the bore of the shank 11, and the tie which is sewed or otherwise secured to the member 20 shown in Figure 5 is now brought into use. It is only necessary to slide the member 20 within the hollow shank 11 until the opening 21 is brought into alignment with the slide 15, after which the slide is depressed so that the reduced extension 18 is received by the opening 21 of the member 20, thereby hold-

ing the component parts of the device together and preventing casual derangement of the tie on the collar, but on the contrary always holding it in its proper position to present a neat appearance.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

What I claim is:

1. A combined collar button and tie fastener comprising separable members, one member including a base and a hollow shank projecting centrally therefrom, and a head from one end of the shank having an inclined surface, the other member including a plate, and a shank projecting centrally therefrom and adapted to be received by the shank of the first mentioned member, said plate being arranged obliquely on its shank to assume a position in parallel relation with

the incline surface of said head when the parts are associated, and means for holding said members together for the purpose specified.

2. A combined collar button and tie fastener comprising separable members, one member including a base having a transverse slot, a hollow shank projecting centrally from the base, and a slide mounted to operate in the slot of said base, the other member including a plate adapted to be secured to the tie, and a shank projecting centrally from said plate and adapted to be received by the hollow shank of the first mentioned member, said plate being arranged obliquely with respect to its shank, whereby the tie can be arranged in proper position with relation to the collar, and said shank of the second mentioned member having an opening adapted to receive said slide whereby the parts are held immovably associated for use.

In testimony whereof I affix my signature.

CHARLES A. BELL.
